Primary Examiner—Mark A Goodwin*(74) Attorney, Agent, or Firm*—Michael J. Striker(57) **CLAIM**

I claim the ornamental design for a harvester spout, as shown and described.

DESCRIPTION

FIG. 1 is perspective view of a harvester spout showing my new design;

FIG. 2 is a side view thereof;

FIG. 3 is a front view thereof;

FIG. 4 is a rear view thereof;

FIG. 5 is a rear perspective view thereof;

FIG. 6 is a top view thereof; and,

FIG. 7 is the opposite side view of FIG. 2 thereof.

The broken line showing of a harvester is included for the purpose of illustrating environmental structure and forms no part of the claimed design.
